UNITED STATES PATENT OFFICE.

EMMA W. HAST, OF LOUISVILLE, KENTUCKY.

SANITARY APPLIANCE.

1,294,099.

Specification of Letters Patent. Patented Feb. 11, 1913.

Application filed July 27, 1912. Serial No. 247,020.

To all whom it may concern:

Be it known that I, EMMA W. HAST, a citizen of the United States, residing at Louisville, in the county of Jefferson and State of Kentucky, have invented certain new and useful Improvements in Sanitary Appliances, of which the following is a specification.

This invention relates to improvements in sanitary appliances for toilet seats. Articles of this type, which are ordinarily made of paper sheets used but once, owing to their formation or construction involve considerable waste of material, and it has therefore been my primary object to provide an article designed to eliminate the waste as much as possible while possessing sufficient structure, so to speak, to adequately afford the desired protection.

To be more specific, these former protective sheets usually are made of such size as to extend over the complete seat, when as a matter of fact this is not essential; the sheets furthermore when cut were provided with an opening to coincide with the toilet seat opening by cutting out the major portion of the central part of the sheet, this cut out part being discarded to waste. As distinguished from this my invention embodies a sheet which covers substantially only one-half of the toilet seat,—the front portion where the protection is desired,—and the material of the sheet when providing for the toilet seat opening is simply slit to enable the edges of the slit portions to be bent or folded in such manner as to provide retaining flaps which hold the sheet in place upon the seat until the user is seated.

It is further an object of this invention to arrange individual sheets of the above type in a convenient package to enable them to be readily carried in traveling from place to place so as to be accessible for use when required.

For a full understanding of the present invention, reference is to be had to the following description, and the accompanying drawing, in which:

Figure 1 is a perspective view showing the application of the protective device to the toilet seat;

Fig. 2 is a plan view of one of the sheets;

Fig. 3 is a perspective view showing the sheets made up into package form; and

Fig. 4 is a perspective view of the tablet in form of the sheets.

Throughout the following detail description and on the several figures of the drawings, similar parts are referred to by like reference characters.

In the drawing, 1 denotes the sheet body which it will be observed in Fig. 2 is fan-shape in form, having a narrow extension 2 at one side. The sheet at the other side, or just opposite to the extension aforesaid is slit along the lines 3, 3, longitudinally of the sheet, to a point approximately centrally thereof, to thereby form a tongue, 4. In addition the edges of the sheet laterally of the tongue are slit in a direction substantially transversely of the sheet body, this to enable the material to be readily bent inwardly or downwardly as shown at 5, when the sheet is applied to the seat as shown in Fig. 1 in conformation with the seat opening. It will be noted that the tongue 4 is also bent inwardly of the opening, and likewise the extension 2 is bent so as to engage about the forward edge of the seat, the tongue and extension serving to hold the sheet in place. The tongue 4 also serves as a splash guard.

Sheets thus formed may be suitably disposed at convenient places in toilets, but I have disclosed two preferred types of multiple sheet arrangements, as shown in Figs. 3 and 4. In the former, I provide the sheets in a folder or envelop 6 constructed to entirely inclose a suitable number of sheets which are preferably attached to the folder by staples 7. In this arrangement it is preferable to fold upwardly the extensions 2 in groups as indicated at 8 as this disposes the bulk to better advantage and in addition makes it easy to remove the individual sheets one at a time for use. This package form is convenient for traveling purposes.

In the form of Fig. 4 the sheets are simply stapled to the backing sheet 9 as a tablet and this unit may be hung in a convenient place in the toilets adjacent to the seats.

The device is of simple form and is economical in construction, since the central portion is not wasted, this being of especial consideration during the existence of scarcity of paper and high cost of material.

Having thus described my invention, what I claim as new is:

A sanitary appliance for toilet seats which

2
consists of a sheet of suitable material of a size to extend over substantially one-half of the seat, said sheet being formed at one side with an extension adapted to be bent down-
5 wardly over the front edge of the sheet, said sheet being slit at its other side at spaced points to form a tongue from the central portion of the material bendable down-

wardly to engage the forward edge of the seat opening, the edges of the slit portion of 10 the sheet at each side of the tongue being slit substantially transversely of the sheet to provide bendable flaps for engagement with the lateral edges of the seat opening.

In testimony whereof I affix my signature. 15
EMMA W. HAST.
